CLAIM

The ornamental design for a self-adjusting groove joint plier,
as shown and described.

DESCRIPTION

FIG. 1 is a perspective view of a self-adjusting groove joint plier showing our new design, looking upwardly at the bottom and right side thereof;

FIG. 2 is a left side elevational view thereof;

FIG. 3 is a right side elevational view thereof;

FIG. 4 is a top plan view thereof;

FIG. 5 is a bottom plan view thereof;

FIG. 6 is a rear elevational view thereof; and,

FIG. 7 is a front elevational view thereof.
